STOCK QUOTATION PROJECTING MACHINE

Eric J. Anderson, Brooklyn, N. Y., assignor to
News Projection Corporation, New York, N. Y.,
a corporation of New York

Application June 18, 1935, Serial No. 27,153
Renewed September 24, 1938

13 Claims. (Cl. 271—2.3)

This invention relates to stock quotation projecting machines in general.

Among the objects of the present invention, it is aimed to provide an improved stock quotation projecting machine in which there is provided a tape pulling roller including a continuously operating motor and a device for disconnecting the driving relation of the tape pulling roller with the motor in cooperation with a tape anchoring means at the light aperture which will preserve the tape smooth at the light aperture both when the tape is being drawn by the tape pulling roller and when the tape pulling roller is at rest.

These and other features, capabilities and advantages of the present invention will appear from the subjoined detail description of specific embodiments thereof illustrated in the accompanying drawings in which

Figure 1 is a front elevation of a stock quotation projecting machine made according to the present invention;

Fig. 2 is a fragmental plan view;

Fig. 3 is a section on the line 3—3 of Fig. 1;

Fig. 4 is a fragmental front elevation of another embodiment of the pulling mechanism shown in Fig. 3;

Fig. 5 is a section on the line 5—5 of Fig. 4;

Fig. 6 is a front elevation of still another embodiment of the pulling mechanism shown in Fig. 3; and

Fig. 7 is a fragmental section on the line 7—7 of Fig. 6.

In the embodiment shown in Figs. 1, 2, and 3, the tape 1 is intermittently discharged by the ticker 2 and from it passes under the roller 3 journaled in the bracket 4 on the side of the extension 5 of the lamp housing 16. After passing under the finger 3, the tape 1 passes over the light aperture formed at the upper end of the extension 5 and then passes down under the tape pulling roller 6 journaled in the sleeve 7 pivotally mounted at 8 in the bearings 9 secured to the front of the housing 10.

From the tape pulling roller 6, the tape passes up into engagement with one side of the finger 11 at the lower end of the arm 12 pivotally connected to the upper end of the arm 13 extending from the upper end of the sleeve 14 formed in the extension 15 extending upwardly from the housing 10. From the finger 11, the tape passes to the mandrel of the rewind reel 16.

At the entrance end of the light aperture, there is formed an opening 17 at one end of the branch conduit 18 connected at its lower end with the main conduit 19 connected to the fan or blower inside of the casing 20. At the discharge end of the light aperture, there is formed the opening 21 at the upper end of the branch conduit 22 which likewise is connected to the upper end

of the main conduit 19. The blower or fan in the casing 20 is mounted on the shaft 23 on which is fixed a sheave 24 connected by the spring belt 25 with the sheave 26 on the shaft of the motor 27. The shaft 23 extends into the housing 10 and has fixed thereon the worm 28 in mesh with the worm wheel 29 on the shaft 30. The shaft 30, see Fig. 3, has a gear 31 thereon in position to mesh with the gear 32 on the shaft of the pulling roller 6 journaled in the sleeve 7 when the pulling roller 6 is disposed in its descended or tape pulling position.

For normally urging the tape pulling roller into tape pulling position and therewith the gear 32 to mesh with the gear 31, there is provided the spring 33 connecting the abutment 34 on the end of the shaft of the tape pulling roller 6 with the abutment 35 extending from the lower end of the housing 10.

For maintaining the tape in pulling engagement with the pulling roller 6, there is provided the friction roller 36 journaled on the end of the long arm 37 of a bell crank pivoted at 38 to the front face of the housing 10 and having a short arm 39 connected by the spring 40 to the abutment 41 extending from the front face of the housing 10.

The shaft 30 has also fixed thereon the sheave 42 connected by the spring belt 43 with the sheave 44 fixed on the shaft of the rewind reel 16. The shaft of the rewind reel 16 has a brake drum 45 fixed thereon to be engaged by the brake shoe 46 on the arm 12.

The operation of the embodiment just described is substantially as follows: The fan in the casing 20 will be continuously actuated to effect a drawing action on the tape at the openings 17 and 21 to cause the tape both at the entrance and discharge ends of the light aperture to hug the abutments at such ends, there to iron out any vibrations that may be transmitted to the tape 1 either by the ticker 2 or by the pulling force exercised on the same by the tape pulling roller 6. Furthermore, it will be noted that when the ticker stops and the tape pulling roller 6 comes to rest the drawing action exercised on the tape by the air at the opening 21 will lock the tape 1 against displacement by the tape pulling roller 6, the sucking or drawing force of the air at the opening 21 being so predetermined that it will be sufficient to anchor the tape 1 against displacement when the tape pulling roller 6 comes to rest but not sufficient to interfere with the tape pulling action of the tape pulling roller 6 when the roller 6 is operating to draw the tape 1 across the light aperture.

It will also appear from the foregoing that when the ticker stops and the tape continues to be drawn by the roller 6 and rewind reel 16, it will initially take up the slack in the tape be-

tween the ticker and the tape pulling roller 6 and then draw the tape pulling roller 6 upward about the pivot pin 8 in turn to clear the gear 32 from engagement with the gear 31.

5 Preferably the teeth of the gears 32 and 31 will be very shallow ordinarily just sufficient to cause a frictional driving engagement between the two. Furthermore, the arm of the shaft on which the pulling roller 6 is fixed is shorter than the arm on which the gear 32 is fixed so that a small movement upward of the pulling roller 6 will be sufficient to cause the gear 32 to clear the gear 31. The tension in the tape 1 thereafter continues to pull the finger 11 inward in turn to press the brake shoe 46 into engagement with the brake drum 45 and thereby lock the rewind reel 16 against rotation and cause the spring belt 43 to slip relative to the sheave 44.

The position of the friction roller 36 is such that 20 when the tension in the tape 1 is relieved, the spring 33 will cause the tape 1 on the tape pulling roller 6 to be pressed into driving engagement with the roller 36. It will also appear that the stop 47 will limit the upward movement of the 25 arm 37 with the spring 40 when the pulling roller 6 is drawn upward by the tension in the tape 1 so that the tape pulling roller 6 may effectively clear the roller 36 when the ticker comes to rest and the tension in the tape 1 is increased sufficiently to draw the roller 6 upward into arresting 30 position.

In the embodiment illustrated in Figs. 4 and 5, the tape pulling roller 48 used in place of the tape pulling roller 6 illustrated in the embodiment 35 shown in Fig. 1, is here journaled at the end of the arm 49 of a bell crank pivotally mounted at 50 to the outer face of the gear casing 51. The other arm 52 of such bell crank has a locating pin 53 secured to its outer end for a compression 40 spring 56, said spring abutting against an adjustable screw stop 55 in the abutment 54. The spring 56 normally urges the arm 52 outwardly to press the gears 59 and 60 into mesh and the roller 48 down into contact with the friction 45 roller 57. The tape pulling roller 48 in the present instance is fixed to a shaft 58 journaled in the end of the long arm 49 which shaft in turn has secured to it at its inner end a gear 59 having shallow teeth to engage and mesh with the teeth 50 of the gear 60 fixed on the shaft 61, and drivingly connected to the motor 62 in the same way that the shaft 7 is drivingly connected to the motor 27. Here with this embodiment when the ticker stops and the tension is increased in the tape 62, the 55 tape pulling roller 48 and gear 59 will rock about the pivot point 50 to clear the gear 60 and friction roller 57.

In the embodiment illustrated in Figs. 6 and 7, the tape pulling roller 63 used in place of the tape 60 pulling roller 6 of the embodiment illustrated in Fig. 1 is fixed to a shaft 64 journaled in the end of the arm 65 pivotally connected at 66 to the outer face of the casing 67. The shaft 64 has fixed thereon the sheave 68 which is connected by the 65 spring belt 69 with the sheave 70 on the shaft 71 of the gear 72 drivingly connected to the electric motor not shown in the same way that the gear 31 is drivingly connected to the motor 27 of the embodiment shown in Fig. 1.

70 The arm 65 is provided with a spring 73 to yieldably urge it downward and therewith the tape pulling roller 63 and the tape 74 into tape pulling engagement with the friction roller 75 and at the same time to tension the spring belt 75 75 69 so that the sheaves 68 and 70 will bear an

effective driving relation to one another. With this embodiment when the ticker stops, and the tension in the tape 74 is sufficiently increased, it will raise the tape pulling roller 63 and the sheave 68 to rock about the pivot point 66 thereby to bring the tape pulling roller 63 out of driving relation with the friction roller 75 and the sheave 68 out of driven relation with the sheave 67.

It is obvious that various changes and modifications may be made to the details of construction 10 without departing from the general spirit of the invention as set forth in the appended claims.

I claim:

1. The combination with a support, of a tape puller for pulling the tape across said support 15 as it is supplied thereto, and pneumatic means independent of said tape puller for pneumatically hugging the tape to the entrance and discharge ends of said support both when the tape is moving and at rest, said pneumatic means consisting of a 20 blower, a main suction conduit connected to said blower and branch conduits terminating in orifices disposed at the entrance and discharge ends of said support connected to said main conduit, the hugging action exercised by said pneumatic 25 means on the tape being uniform whether the tape puller is operating or at rest.

2. The combination with a support, of a tape engaging and pulling roller for pulling the tape across said support as it is supplied thereto, a 30 continuously operating motor, a drive operatively connected to said motor, a take-up reel, slippage means drivingly connecting said take-up reel with said drive, and yieldable means for normally maintaining said pulling roller in driving relation with said drive but yieldable to be drawn out of driving relation by the tension in the tape transmitted directly to the tape pulling roller by the tape while in engagement therewith when the supply is interrupted and the take-up reel continues to operate.

3. The combination with a support, of a tape engaging and pulling roller for pulling the tape across said support as it is supplied thereto, a continuously operating drive member, a take-up 45 reel, slippage means drivingly connecting said take-up reel with said drive member, a yieldable support for said pulling roller, and a driven member fixed to rotate with said roller, said yieldable support normally maintaining said driven member and thereby said pulling roller in driving relation with said drive member but yieldable to be drawn out of driving relation by the tension in the tape transmitted directly to the tape pulling roller by the tape while in engagement therewith when the supply is interrupted and the take-up reel continues to operate.

4. The combination with a support, of a tape engaging and pulling roller for pulling the tape across said support as it is supplied thereto, a 60 continuously operating drive member, a take-up reel, slippage means drivingly connecting said take-up reel with said drive member, a driven member fixed to rotate with said tape pulling roller, a pivotally mounted arm, said driven member and roller being journaled to the free end of said arm, and yieldable means for normally maintaining said driven member and therefore said tape pulling roller in driving relation with said drive member but yieldable to be drawn out of 65 driving relation by the tension in the tape transmitted directly to the tape pulling roller by the tape while in engagement therewith when the supply is interrupted and the take-up reel continues to operate.

5. The combination with a support, of a tape pulling roller for pulling the tape across said support as it is supplied thereto, a continuously operating drive member, a rewind reel, a driven member fixed to rotate with said tape pulling roller, a pivotally mounted arm, said driven member and roller being journaled to the free end of said arm, yieldable means for drivingly connecting said rewind reel to said drive member, 5 second yieldable means for normally maintaining said driven member and therefore said tape pulling roller in driving relation with said drive member but yieldable to be drawn out of driving relation by the tension in the tape transmitted to the tape pulling roller when the supply is interrupted and the rewind reel continues to operate, and a brake device responsive to deflections in the tape subsequently to anchor said rewind reel against rotation after the supply has 10 been interrupted and the tape pulling roller has come to rest.

6. The combination of an inspection area, such as a light aperture, a tape puller for pulling tape across said area as it is supplied thereto, and 15 pneumatic means independent of said tape puller for pneumatically hugging the tape to the entrance and discharge ends of said area, but clear of said area, both when the tape is moving and when at rest in order to maintain the tape smooth 20 and taut at the inspection area.

7. The combination of an inspection area, such as a light aperture, a tape puller for pulling tape across said area as it is intermittently supplied thereto, and suction means independent of said 25 tape puller for hugging the tape both to the entrance and discharge ends of said area, but clear of said area, both when the tape is moving and when at rest, said suction means effecting a reaction to the tape puller sufficient to iron 30 out the vibrations transmitted thereto by the intermittent supply and to anchor the tape against displacement when the supply is interrupted and the tape puller comes to rest but not sufficient 35 to interfere with the effective pulling of the tape across said area when said tape puller is operating.

8. The combination with a support, of a tape pulling roller for pulling the tape across said support as it is supplied thereto, a continuously 40 operating drive member, a rewind reel, a driven member fixed to rotate with said tape pulling roller, a pivotally mounted arm, said driven member and roller being journaled to the free end of said arm, yieldable means for drivingly connecting said rewind reel to said drive member, 45 and second yieldable means for normally maintaining said driven member and therefore said tape pulling roller in driving relation with said drive member but yieldable to be drawn out of driving relation by the tension in the tape when the supply is interrupted and the rewind reel continues to operate.

9. The combination of an inspection area, such as a light aperture, a tape puller for pulling the tape across said area as it is supplied thereto, a 50 continuously operating drive member, a take-up reel, slippage means drivingly connecting said take-up reel to said drive member, a yieldable support for said puller, and a driven member drivingly connected to rotate with said puller, said yieldable support normally maintaining said driven member and thereby said puller in drivingly relation with said drive member but yield-

able to enable said driven member to be drawn out of driving relation with said drive member by the tension in the tape transmitted to the tape puller by the tape when the supply is interrupted and the take-up reel continues to operate.

10. The combination of an inspection area, such as a light aperture, a tape puller for pulling the tape across said area as it is supplied thereto, a continuously operating drive member including a gear, a take-up reel, slippage means drivingly connecting said take-up reel to said drive member, a pivotally mounted arm on which said puller is mounted, a second gear mounted on said arm and drivingly connected to said puller, and means normally maintaining said second gear in mesh with said first gear but yieldable to enable said second gear to be drawn out of driving engagement with said first gear by the tension in the tape transmitted to the tape by the puller when the supply is interrupted and the take-up reel continues to operate.

11. The combination of an inspection area, such as a light aperture, a tape puller for pulling the tape across said area as it is supplied thereto, a continuously operating drive member including a 25 sheave, a take-up reel, slippage means drivingly connecting said take-up reel to said drive member, a pivotally mounted arm on which said puller is mounted, a second sheave drivingly connected to said puller, a yieldable belt drivingly connecting said second sheave to said first sheave, and means normally maintaining said belt in drive transmitting engagement with said sheaves, said means being yieldable to enable said belt sufficiently to free said sheaves from drive transmitting 30 engagement by the tension in the tape transmitted to the tape puller by the tape when the supply is interrupted and the take-up reel continues to operate.

12. The combination of an inspection area, such as a light aperture, a tape puller for pulling the tape across said area as it is supplied thereto, a continuously operating drive member including a gear, a take-up reel, slippage means drivingly connecting said take-up reel to said drive member, a pivotally mounted bracket having two arms, a driven member including a second gear drivingly connected to said puller and journaled in one arm, and a spring connected to said other arm normally to maintain said second gear in drive transmitting engagement with said first gear but yieldable to enable said second gear to be drawn out of driving relation with said first gear by the tension in the tape transmitted to the tape puller by the tape when the supply is interrupted and the take-up reel continues to operate.

13. The combination of an inspection area, such as a light aperture, a tape puller for pulling the tape across said area as it is supplied thereto, a continuously operating drive member, a take-up reel, a yieldable support for said puller, and a driven member drivingly connected to rotate with said puller, said yieldable support normally maintaining said driven member and thereby said puller in driving relation with said drive member but yieldable to enable said driven member to be drawn out of driving relation with said drive member by the tension in the tape transmitted to the tape puller by the tape when the supply is interrupted and the take-up reel continues to operate.
